UNITED STATES PATENT OFFICE.

THOMAS L. DUSSEAU, OF PHILADELPHIA, PENNSYLVANIA, ASSIGNOR TO BIDDLE-GAUMER COMPANY, OF PHILADELPHIA, PENNSYLVANIA, A CORPORATION OF PENNSYLVANIA.

DESIGN FOR A BRACKET ARM FOR A LIGHTING FIXTURE OR SIMILAR ARTICLE.

Application filed February 27, 1922. Serial No. 902. Term of patent 7 years.

To all whom it may concern:

Be it known that I, THOMAS L. DUSSEAU, a citizen of the United States, and a resident of Philadelphia, Pennsylvania, have invented a new, original, and ornamental Design for a Bracket Arm for Lighting Fixtures or Similar Articles, of which the following is a specification, reference being had to the accompanying drawings, forming part thereof, in which:

Figure 1, is a side elevation showing the

design for a bracket arm forming the subject of my invention.

Fig. 2, is a front elevation of the same.

I claim:

The ornamental design for a bracket arm for a lighting fixture or similar article as shown in the accompanying drawings.

In witness whereof I have signed this specification.

THOMAS L. DUSSEAU.
